CONDENSER MICROPHONE

Erwin Gerlach, Berlin, Germany; vested in the
Alien Property CustodianApplication July 15, 1939, Serial No. 284,647
In Germany July 25, 1938

1 Claim. (Cl. 179—111)

In condenser or electrostatic microphones of high sensitiveness the space intervening between the surfaces of the electrodes amounts to only a few microns. Hence, there is a risk of this gap undergoing alterations as a result of unequal 5 thermal expansion of the electrode supports.

This risk is eliminated according to the invention by making the said electrode supporting or holding means of the same material or of a kind of material which has the same heat expansion 10 coefficient, and by mounting them upon a common plate or slab of insulating material. Hence, figured from the surface of the said plate as the reference surface, there will thus arise no differences in thermal expansion in the direction towards the face of the electrodes.

The invention shall now be described in more detail by reference to an exemplified embodiment thereof illustrated in the appended drawing. Both figures of the drawing show sectional 20 views of condenser microphones.

Referring to Fig. 1, one of the electrodes 1 consists of a diaphragm which by means of a screw-threaded ring 2 and interposition of an annular washer 4 is screwed fast upon the electrode support or mount 3. The second electrode 6 is of the apertured or perforated (sieve) type. It is secured to the electrode support 10. The electrode support 3 has an offset 13 which comes to bear upon the insulation plate 5, while electrode support 10 bears with its under side 11 upon the same insulation plate 5. The latter is in pressure engagement with the offset or recess 13 by means of the screw-threaded ring 15, with an annular washer 14 being interposed. Connection 30 between the electrode support 10 and the insulation plate 5 is established by means of a screw 9.

The electrode supports 3 and 10 are made of the same material, that is, brass. The insulation plate 5 consists of glass or some other insulator such as amber. The upper face of the insulation plate 5 which bears against the surfaces 11 and 13 is polished so as to be perfectly smooth and level.

If, then, upon fluctuations of the temperature, the electrode mount 10 experiences expansion, the electrode support 3 will expand similarly, and the result is that the distance or gap between the electrodes 1 and 6 will always be constant and stable.

Fig. 2 shows a similar embodiment in which, however, the first or outer electrode support consists of several constituent parts rather than only one part. The diaphragm 1 is shrunk-fitted by means of a ring 2 and another, interposed ring 4 upon the supporting ring 3, the latter, in turn, being united with the support 30 by means of the screw 23. The offset portion 31 of the support bears upon the surface of the insulation plate 5. The second perforated electrode 6 is secured upon the electrode support or holder part 10 which rests upon a yielding plate 16, which, on the other hand, comes to bear upon a projection 17 of the insulation plate 5. In this embodiment the distance separating the electrodes 1 and 6 is adjustable by the aid of a set screw 9. Parts 3, 30, 10 and 16 consist of a sort of material that has the same coefficient of thermal expansion.

What is claimed is:

A microphone comprising a diaphragm forming a movable electrode, a shouldered support for said movable electrode, a second electrode, a support for said second electrode located within said shouldered support, an insulating plate for supporting said second electrode and located at said shouldered portion of said first mentioned support, projections on said insulating plate, a resilient plate resting on said projections, and means associated therewith to adjust the spacing between the electrodes, both of said supports being of material having the same thermal expansion coefficient whereby there will be substantially no change in the spacing between said electrodes due to thermal expansion of said supports.

ERWIN GERLACH.
